(57) **CLAIM**

The ornamental design for a housing for electrical junction, as shown and described.

DESCRIPTION

FIG. 1 is a top perspective view of a housing for electrical junction showing our new design;

FIG. 2 another top perspective view thereof;

FIG. 3 is a bottom perspective view thereof;

FIG. 4 is another bottom perspective view thereof;

FIG. 5 is a top plan view thereof;

FIG. 6 is a bottom plan view thereof;

FIG. 7 is a side elevation view thereof;

FIG. 8 is an opposite side elevation view thereof;

FIG. 9 is an end elevation view thereof; and,

FIG. 10 is an opposite end elevation view thereof.

The broken lines depicting three cylinders protruding from the ends of the housing for electrical junction are for the purpose of illustrating environmental structure and form no part of the claimed design. The remaining broken lines are for the purpose of illustrating portions of the housing for electrical junction and form no part of the claimed design.
